BERNARD F. STENZ, OF NEW YORK, N. Y., ASSIGNEE TO SIMPLEX LITHOGRAPH COMPANY, OF NEW YORK, N. Y., A CORPORATION OF NEW YORK.

SAMPLE-TAB.

1,283,592.

Specification of Letters Patent. Patented Nov. 5, 1918.

Application filed August 5, 1916. Serial No. 113,317.

To all whom it may concern:

Be it known that I, BERNARD F. STENZ, a citizen of the United States, and resident of New York city, borough of Manhattan, in the county and State of New York, have invented a new and Improved Sample-Tab, of which the following is a full, clear, and exact description.

The object of the present invention is to produce a sample tab so constructed that not only will there be a saving in the cost of the materials used, but a sample tab which shall be of lighter weight and will lie flatter as compared to those made heretofore, and by the use of which a saving in the cost of transportation will be effected.

A further object is to materially reduce the cost of labor in the production of such sample tabs.

The present invention is illustrated in the accompanying drawing in which are also shown sample tabs as heretofore constructed.

In the drawing, Figure 1 is a plan view of the blank from which the sample tabs are produced, also illustrating the method of manufacture.

Fig. 2 illustrates a front view of the improved sample tab.

Fig. 3 shows an edge view of one of the longer sides.

Fig. 4 shows a front view of the sample tab as heretofore constructed, and

Fig. 5 shows a back view thereof.

The sample tab illustrated in the drawing, as heretofore constructed, as shown in Figs. 4 and 5 of the drawing, consisted of a mount *a* of flexible material such as cardboard, the central portion of which was substantially an elongated rectangle provided at its opposite ends with ears *a*¹ and *a*², and as usually constructed the ear *a*¹ was somewhat longer than the ear *a*² and carried upon its front face a number identifying the sample of fabric mounted thereon.

The ears *a*¹ and *a*² are intended to be fitted into complementary slots or openings formed in a leaf of a sample book, or other supporting carrier, leaving the body portion of the tab and the sample of goods thereon exposed, all as will be clearly understood by those skilled in this art.

As heretofore constructed, and as shown in Figs. 4 and 5, the sample of textile fabric *a*³ to be displayed was cut of such a size as

to substantially cover the elongated rectangular body portion of the mount *a* and was lapped over upon the under surface, as shown at *a*⁴, and was secured on the mount by any suitable adhesive.

This method of producing sample tabs is costly and slow, as the individual samples of textile fabric must be first cut up in suitable sizes, and then each piece supplied with an adhesive and carefully folded about and secured upon each individual mount.

My improved sample tab, as shown in Figs. 2 and 3, comprises the usual mount *b* having the ears *b*¹ and *b*², and the elongated rectangular body portion, upon one face of which is mounted a textile sample *b*³, the textile sample extending substantially across the rectangular body portion of the mount *b* and having its upper and lower edges coincident with the upper and lower edges of the rectangular body portion of the mount.

In manufacturing my improved sample tab, I provide a strip of flexible material suitable for the purpose, and preferably a strip of cardboard *c*, said strip being of an indefinite length and of a width preferably corresponding to the length of the mounts to be cut therefrom in order to eliminate and reduce waste to a minimum.

Upon one surface of the strip *c*, I secure a strip of fabric *c*¹ by a suitable adhesive, and as shown in Fig. 1 of the drawing, the strip of fabric *c*¹ is narrower than the strip *c* and is laid on the strip *c*, so that it will be closer to one edge of the strip *c* than it will to the other edge. The blank thus formed is thereafter cut up by a suitable cutting mechanism, preferably so constructed that it will sever at a single cut from the blank a plurality of sample tabs as shown in Fig. 1. Each operation of the cutting tool will sever from the strip or blank as many of the tabs with the projecting ears as the cutter is formed to cut, and the operation will result in only a slight waste of the cardboard by the formation of the tapering tabs, there being no waste whatever of the textile material. Of course, a single sample tab may be cut from the blank, but in practice I use a cutter having a cutting edge formed to cut a number of the sample tabs from the blank at a single operation.

The construction of my improved "sample tab" is such that I am enabled to produce

2
in a given length of time, and with a minimum amount of labor, a greatly increased number of sample tabs as compared with the old forms, and effecting a large saving

5 in the cost of labor and materials, more particularly in the expensive textile materials employed, while at the same time I decrease the weight and bulkiness of the sample tabs.

Sample tabs as thus formed will be of 10 less bulk than the old form, and will lie flatter when inserted in the slots of the leaf of the sample book.

Having thus described my invention, I claim as new and desire to secure by Letters

15 Patent:

1. A sample tab comprising a suitable mount of flexible material having a body portion with integrally formed projecting ears at the opposite ends of said body portion, and a sample adhesively secured upon one face of the body portion with its lateral edges disposed adjacent to the projecting ears, and its upper and lower edges coincident with the upper and lower edges of the body portion, the sample being wholly located upon one face of the body portion of the mount.

2. A sample tab comprising a suitable

mount of flexible material having a body portion with integrally formed projecting 30 tapering ears at the opposite ends of said body portion, and a sample adhesively secured upon one face of the body portion with its lateral edges disposed adjacent to the projecting tapering ears, and its upper 35 and lower edges coincident with the upper and lower edges of the body portion, the sample being wholly located upon one face of the body portion of the mount.

3. A sample tab comprising a flexible 40 mount provided at opposite ends with projecting ears and a sample of textile fabric adhesively secured thereon and located wholly upon one face of the body portion of said mount, the upper and lower edges 45 of the sample of textile fabric being coincident with the upper and lower edges of the mount.

In testimony whereof I have signed my name to this specification in the presence of 50 two subscribing witnesses.

BERNARD F. STENZ.
